(57) **CLAIM**

The ornamental design for a vehicle, as shown and described.

DESCRIPTION

FIG. 1 is a left side elevational view of a vehicle showing our new design;
FIG. 2 is a right side elevational view thereof;
FIG. 3 is a front elevational view thereof;
FIG. 4 is a rear elevational view thereof;
FIG. 5 is a top plan view thereof;
FIG. 6 is a front perspective view thereof;
FIG. 7 is a front perspective view thereof with the gullwing roof components in open position;
FIG. 8 is another front elevational view thereof with the gullwing roof components in open position;
FIG. 9 is a right side perspective view thereof with the right rear sliding door in open position;
FIG. 10 is another top plan view with the right rear sliding door in open position;
FIG. 11 is another right side elevational view thereof with the right rear sliding door in opened position;
FIG. 12 is another top plan view thereof with both the right and left side gullwing roof components and rear sliding doors in open position;
FIG. 13 is another front elevational view thereof with both the right and left side gullwing roof components and rear sliding doors in open position;
FIG. 14 is another rear elevational view thereof with both the right and left side gullwing roof components and rear sliding doors in open position;
FIG. 15 is another right side elevational view thereof with both the right side gullwing roof component and rear sliding door in open position;
FIG. 16 is another right side perspective view thereof with both the right side gullwing roof component and rear sliding door in open position; and,
FIG. 17 is another left side perspective view thereof with both the left side gullwing roof component and rear sliding door in open position.
The broken lines shown throughout the drawing views are for environmental and illustrative purpose and form no part of the claimed design.

1 Claim, 15 Drawing Sheets
